(57) **CLAIM**

The ornamental design for a cooler bag with beads, as shown and described.

DESCRIPTION

FIG. 1 is a front view of the cooler bag, the rear view being a mirror image;

FIG. 2 is a left side view of the cooler bag, the right side being a mirror image;

FIG. 3 is a top view of the cooler bag; and,

FIG. 4 is a bottom view of the cooler bag.

The broken lines of FIG. 2 are for purposes of illustration only and form no part of the claimed design.
